US00D853790S

(12) **United States Design Patent** (10) **Patent No.:** **US D853,790 S**
(45) **Date of Patent:** **** Jul. 16, 2019**

(54) **BOTTLE**

(71) Applicant: **PepsiCo, Inc.**, Purchase, NY (US)

(72) Inventors: **Drew Alexander Read Palin**, Kenilworth, IL (US); **Sean Joseph Huls**, Chicago, IL (US); **Brandon Scott Rhodes**, Chicago, IL (US); **Xavi Cortadellas**, Miami Beach, FL (US); **Tucker Fort**, Brooklyn, NY (US); **Laura Sink**, Brooklyn, NY (US); **Alexander Ian James Wastney**, Brooklyn, NY (US); **John Lester Ostby**, Seattle, WA (US); **Matthew Schmunk**, Portland, OR (US)

(73) Assignee: **PepsiCo, Inc.**, Purchase, NY (US)

(**) Term: **15 Years**

(21) Appl. No.: **29/609,844**

(22) Filed: **Jul. 6, 2017**

Related U.S. Application Data

(63) Continuation of application No. 29/584,894, filed on Nov. 18, 2016, now Pat. No. Des. 794,391, which is a continuation of application No. 29/535,914, filed on Aug. 11, 2015, now Pat. No. Des. 774,357.

CLAIM

The ornamental design for a bottle, as shown and described.

DESCRIPTION

FIG. 1 is a top front perspective view of a bottle showing the claimed design;

FIG. 2 is a bottom front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the bottle that form no part of the claimed design.

1 Claim, 7 Drawing Sheets
